UNITED STATES PATENT OFFICE

93,812

DESIGN FOR A LIQUID FUEL COOK STOVE

William T. Bradbury, Kankakee, Ill., assignor to
Florence Stove Company, Gardner, Mass., a
corporation of Massachusetts

Application February 28, 1934, Serial No. 50,897

Term of patent 7 years

To all whom it may concern:

Be it known that I, WILLIAM T. BRADBURY, a citizen of the United States, residing at Kankakee, in the county of Kankakee, and State of Illinois, have invented a new, original, and ornamental Design for a Liquid Fuel Cook Stove, of which the following is a specification, reference being had to the accompanying drawing, forming part thereof.

The figure is a perspective view of a liquid fuel cook stove, showing my new design.

I claim:

The ornamental design for a liquid fuel cook stove substantially as shown.

WILLIAM T. BRADBURY.
